UNITED STATES PATENT OFFICE.

WILLIAM M. KELLY, OF WESTFIELD, NEW JERSEY, ASSIGNOR TO AMERICAN TYPE FOUNDERS COMPANY, OF JERSEY CITY, NEW JERSEY, A CORPORATION OF NEW JERSEY.

DUCTOR-ROLL MECHANISM.

Application filed April 14, 1923. Serial No. 632,078.

The present invention relates to printing presses, and particularly to the inking mechanism thereof.

One of the objects of this invention is to effect automatically an even coaction between the ductor roll and the fountain and transfer rolls even if their axes are not quite parallel. This object is carried out, according to the present invention, by providing a yielding connection between the ductor roll and its oscillating means, whereby the ductor roll is permitted independent bodily movements relative to said oscillating means. The yielding mounting of the ductor roll permits each element of its cylindrical surface to contact the corresponding elements of the fountain roll and transfer roll, so that the ink is evenly distributed on the ductor roll by the fountain roll and is, in turn, evenly distributed over the transfer roll by the ductor roll. The ultimate effect is a perfectly even inking of the form bed.

Another object of the present invention is to provide means to stop the feeding of the ink to the rolls under certain conditions, as when no sheets are being fed to the impression cylinder. This object is attained, in the embodiment of the invention illustrated herein, by the provision of a stop governed by the sheet detector, and operable into a position where it prevents the ductor roll from contacting with the fountain roll, whereby the feeding of the ink is discontinued when said stop is moved to operative position upon failure to feed a sheet. Thus an excessive accumulation of ink on the bed rolls and consequent blackening of the printed sheets are prevented.

Other objects and features of novelty will be apparent from the description taken in connection with the drawings, in which:

Figure 1 is a side elevation of the feeder end of a printing press, showing the press inking mechanism and parts of a sheet feeding device;

Figure 2 is a view of the inking mechanism shown in Figure 1, looking from the opposite side;

Figure 3 is an enlarged side elevation, partly in section, of the fountain, ductor and transfer rolls, showing one construction for mounting and controlling the ductor roll in accordance with the present invention; and

Figure 4 is a fragmentary plan view of

parts shown in Figure 3, the fountain and transfer rolls being omitted.

The present invention relates only to the mounting and control of the ductor roll. It is independent of any particular construction of press, inking mechanism or sheet feeding devices. Hence the press and parts mentioned may be referred to only in a general way.

The press illustrated is of the bed-and-cylinder type. The construction of the inking mechanism, with the exception of the mounting of the ductor roll, is the same as that described in my copending application, Serial No. 490,290, filed August 6, 1921, now Patent No. 1,651,774. Said mechanism comprises an ink fountain 1, a fountain roll 2, a ductor roll 3, a transfer roll 4, vibrating rolls 5 and form rolls 6. The fountain roll is rotated step by step by the ratchet mechanism shown in Figure 2. The ductor roll is supported by a shaft 7 which is oscillated by means of a cam 8, lever 8^a, link 8^b and arm 8^c secured to shaft 7, shown in Figure 2, as in my copending application.

The ductor roll 3 is supported on shaft 7 by means of the following construction. Rotatably mounted on shaft 7 near each end thereof is an arm 9 having in the free end thereof an upwardly opening slot which receives a journal 10 of the ductor roll. The journals are locked in said slots by means of latches 11 pivoted on arms 9. Springs 12 attached to the tails of said latches and to pins projecting from the hubs of arms 9 tend to hold said latches in locking position, which is the position illustrated in Figure 3. Fixed on shaft 7 adjacent to and inside each arm 9 is a member 13 which has a pair of spaced projections 14. Each arm 9 has a lug 15 projecting from the outer face thereof between the projections 14. Mounted in an aperture of each lug 15 is a pin 16 which projects on each side of the lug, and coil springs 17 surround the projecting ends of the pin and bear at their ends against the lug 15 and projections 14, respectively. This construction provides a yielding connection between the ductor roll and operating shaft 7, at each end of the roll. As the yielding connections are independent of each other the roll may, if necessary, be moved more at one end than the other to effect contact throughout the coacting elements of the ductor roll and the foun-

100

105

tain roll, on the one hand, and of the ductor roll and transfer roll 4, on the other hand, it being understood that the throw of shaft 7 is slightly more than necessary to effect 5 mere contact of the ductor roll with the coacting rolls, that is, the ductor roll is yieldingly pressed into contact with said coacting rolls, whereby a perfect contact is obtained irrespective of any lack of parallelism of the co- 10 acting elements due to wear of the bearings or other causes.

The second named object of the invention is carried out by the following construction. A shaft 18, beneath and parallel to the fountain roll, is journaled at each end in a bracket 19 secured to the frame of the press. This shaft has fixed thereto a pair of fingers 20 which are located in the planes of the arms 9 and which are adapted to be moved into and 20 out of the path of said arms, to control the throw of the ductor roll towards the fountain roll. Means for rotating shaft 18 under the control of the sheet detector is provided whereby said shaft may be rotated to throw 25 the fingers 20 into abutting relation to the arms 9 and so stop the ductor roll short of the fountain roll, upon failure of the sheet feeding mechanism to feed a properly registered sheet and which will move said fingers 30 out of the path of said arms when sheets are again fed to the impression cylinder. The connection illustrated consists of an arm 21 fixed to an end of shaft 18 and a link 22 connecting said arm to a bell crank 23 which is 35 fulcrumed on the frame of the feeder adjacent a link 24 which is operated downwardly when no sheet is fed to the impression cylinder or when a sheet is fed out of register or in a crumpled condition. The sheet detector mechanism partly illustrated is fully 40 shown and described in my Patent 1,469,515, granted October 2, 1923, and reference may be had thereto, if desired, for a fuller understanding of the construction and operation 45 of said mechanism. It is to be understood, however, that the present invention is not limited to any particular sheet detector. From the construction described, it will be understood that when no sheets are being fed 50 or when a sheet is out of register shaft 18 will be rotated in a counter-clockwise direction, looking at Figure 3, and the fingers 20 moved into the position shown in said figure. In this position the ends of the fingers will 55 abut surfaces 25 formed on arms 9 when the ductor roll is moved towards the fountain roll and will prevent the ductor roll from contacting with, and receiving ink from, the fountain roll.

60 Although an embodiment of the invention has been described in detail, it is to be understood that the invention is not thus limited, but includes modifications and changes that come within the scope of the appended claims.

65 Having thus described the invention what

is claimed as new and desired to be secured by Letters Patent is:

1. In inking mechanism for printing presses, a ductor roll, a shaft journalled parallel to said roll, arms rotatable on said shaft, 70 said ductor roll being supported by said arms, yielding connections between said arms and shaft, means for oscillating said shaft, and a stop normally in inactive position movable into the path of movement of one of said arms 75 to thereby hold the roll from movement.

2. In inking mechanism for printing presses, a fountain roll, a ductor roll, means to oscillate said ductor roll to convey ink from said fountain roll, said means including a yielding connection permitting relative bodily movements of said ductor roll with respect to said means, a sheet detector device and a stop connected thereto and pivoted to swing under its influence into a position below the point of contact of said rolls, to thereby prevent said ductor roll from receiving ink from said fountain roll. 85

3. In inking mechanism for printing presses, a ductor roll, a shaft journalled parallel to said roll, arms rotatable on said shaft, 90 said ductor roll being supported by said arms, yielding connections between said arms and shaft, means for oscillating said shaft, a sheet detector device, and a stop normally in inactive position connected to said sheet detector mechanism and movable thereby into the path of one of said arms. 95

4. In inking mechanism for printing presses, a ductor roll, a support for said roll, 100 means for oscillating said support, a yielding connection between said support and oscillating means, and a stop normally in inactive position movable into the path of movement of said support to thereby limit the throw of 105 said roll.

5. A ductor roll mounting for printing presses, comprising in combination, an ink fountain, a fountain roll, a rock shaft mounted in front of and below said fountain roll, a 110 pair of arms freely mounted on said shaft and having bifurcated ends, a ductor roll having its shaft journaled in said ends, a spring actuated latch normally holding said shaft journaled in said ends, a member fixed to said shaft and having spaced abutments, a lug on one of said free arms yieldingly held between said abutments, a transfer roll, and means for oscillating said shaft to swing said ductor roll from contact with said fountain roll to 115 contact with said transfer roll, and a stop member adapted to be positioned to abut one of said free arms to prevent its swinging the ductor roll into contact with said fountain roll, said yielding mounting of said lug permitting the stop means to prevent the motion of the free arms without interfering with the continuous operation of said oscillating means. 120

6. A ductor roll mounting for printing 130

presses, comprising in combination, an ink fountain, a fountain roll, a rock shaft mounted in front of and below said fountain roll, a pair of arms freely mounted on said shaft, 5 a ductor roll having its shaft journaled in said arms, a member fixed to said shaft and having spaced abutments, a lug on one of said free arms yieldingly held between said abutments, a transfer roll, and means for oscillating said shaft to swing said ductor roll 10 from contact with said fountain roll to con-

tact with said transfer roll, a sheet detector device, and a stop normally in inoperative position connected to said sheet detector mechanism and movable thereby into the 15 path of one of said arms, to thereby limit the throw of said ductor roll, and prevent its contact with the fountain roll.

In testimony whereof I hereunto affix my signature.

WILLIAM M. KELLY.
